CATHODE RAY TUBE

Max Knoll, Berlin, Germany, assignor to Telefunken Gesellschaft für Drahtlose Telegraphie m. b. H., Berlin, Germany, a corporation of Germany

Application August 4, 1934, Serial No. 738,435
In Germany August 1, 1933

5 Claims. (Cl. 250—27.5)

Cathode-rays which, for instance, are produced in a Braun tube which is to be adapted to the reception of television pictures, in order that a highly luminous picture may be created, must be as dense or numerous as feasible, while they should have as little hardness as possible in order that the necessary deflection potentials may not be unduly high.

To fulfill these two requirements, according to the invention, the cathode-rays are accelerated after their emergence from the cathode by the agency of electrodes whose diameter is large in contrast with the cross-section of the cathode-ray pencil, whereupon they are retarded in which state of low velocity they are subjected to deflection, whereupon they are again accelerated. Unless the focussing or concentration of the cathode-rays is accomplished simultaneously by the same electrodes which serve to insure the first acceleration or the retardation, also the focussing is to be effected by additional electrodes of large diameter.

One exemplified embodiment of the invention shall be described in what follows by reference to the attached schematic drawing. Referring to the drawing, 10 denotes the cathode, 11 a disk serving to homogenize the first accelerator field which, for instance, may be in conductive relationship with the cathode. 12, 13, and 14 denote annular electrodes to which is applied a potential that is positive in reference to the cathode 10, to be more precise, the potential applied to electrode 13 is more positive than that at electrode 12. The potential of the electrode 14 is negative relative to that of electrode 13 so that the cathode-rays which travel through the middle of electrode 13 at a fairly high rate of velocity, experience a decrease in speed. Between the electrodes 14 and 15, of which the last-named one surrounds the deflector plates of the Braun tube, is applied the voltage of an auxiliary battery 16 whereby the electrode 15 is maintained at a negative potential relative to the electrode 14 and the next electrode 17 located below the deflector plates. As they enter electrode 15 the cathode-rays are caused to pass through the equipotential surfaces indicated by the broken lines, said surfaces acting in the sense of increased convergence of the cathode-ray pencil. The cathode-rays which in this stage have a still lower speed than at the time they emerged from electrode 14, will be deflected in the deflector plates even by the action of small fields. On leaving electrode 15 the cathode-rays are passed again through curved equipotential surfaces which are likewise shown in the drawing by

dotted lines and which, similarly as in the case of the equipotential surfaces traversed upon the exit from the electrode 15, tend to act in the sense of increased convergence of the pencil of cathode-rays. Impressed upon the electrodes 18—21 in the lower end of the tube being of truncated-cone shape are increasingly more positive potentials so that the potential of electrode 18 is more positive than that of electrode 17, the potential at electrode 19 more positive than that of electrode 18, and so on. The potentials acting at electrodes 17—21 are so graduated that the equipotential surfaces are practically spherical, with the center of the curvature being located between the pairs of deflector plates. Hence, the equipotential surfaces are traversed by the pencil of cathode-rays almost at right angles so that an increase in luminosity, but no additional deflection of the spot upon the screen of the tube will be caused.

It will thus be evident that in a tube of the kind here disclosed cathode-rays in copious quantities will be produced because of the positive potential prevailing at the electrodes 12 and 13; furthermore, that these rays, on the one hand, because of the negative potential of electrode 14 in reference to electrode 13, and, on the other hand, because of the negative potential of the electrode 15 in reference to electrode 14, will have between the deflecting plates but a moderate hardness so that they are readily deflectable, and that, finally, the spot upon the screen of the tube will turn out very bright for reason of the increasing positive potential between the electrodes 17 and 21.

Instead of distinct electrodes 17—21, also a spiral made from resistor material through which an auxiliary current is conducted, could be employed. Similarly, electrodes 12—13 could be replaced by a resistor spiral traversed by an auxiliary current.

In the said spirals each individual turn or the fall of potential occurring along an individual turn can be compared with the voltage between two consecutive electrodes. A spiral with n many turns would then correspond to n many electrodes. In other words, the requisite fields are producible in just as fine a graduation by the use of spirals comprising a great number of turns as by the use of electrodes provided in equally great number.

Aside from the Braun tubes intended for the reception or re-creation of televised pictures, the invention is useful also in tubes working with electron or ion rays. Among these may be mentioned oscillograph tubes, electron-ray tubes with fluo-

rescent screens of the kind used in connection with the recording of sound-films and the like for the photographic recording of acoustic actions, Roentgen-ray tubes, electron tubes used for amplification, rectification, and wave generation, and finally ion-ray tubes for the generation of high potential by kinetic ways and means where similar problems are involved which are solvable by a similar application of the invention.

10 I claim:

1. An electronic device comprising a fluorescent screen structure, an electron emitting surface for producing an electron beam, a plane apertured shielding electrode lying in the plane of the electron emitting surface, a plurality of beam deflecting electrodes, and a plurality of hollow cylindrical electrodes positioned intermediate the deflecting electrodes and the electron emitting surface, and a second plurality of hollow cylindrical electrodes positioned intermediate the deflecting electrodes and the fluorescent screen.
2. An electrode system for a cathode ray tube which comprises a plurality of similar annular cylindrical electrodes, a shielding cylindrical annular electrode in register with the plurality of similar electrodes, a plurality of deflecting electrodes positioned within the shielding electrode, and a plurality of annular conical electrodes in register with the shielding electrode.
3. An electrode system for a cathode ray tube comprising a source of electrons, a shield electrode in register with said source of electrons, a plurality

of similar annular electrodes in register with said source of electrons, a plurality of hollow surface-of-revolution electrodes in register with said first plurality of electrodes, a hollow shielding electrode intermediate the first and second plurality of electrodes, and deflecting electrodes positioned within the shielding electrode.

4. A cathode ray tube comprising an envelope having an end wall, a fluorescent screen on said end-wall, a source of electrons positioned remotely from the end wall, a shield electrode in register with said source of electrons, a plurality of similar annular electrodes in register with said source of electrons, a plurality of hollow surface-of-revolution electrodes in register with said first plurality of electrodes, a hollow shielding electrode intermediate the first and second plurality of electrodes, and deflecting electrodes positioned within the shielding electrode.

5. A cathode ray tube comprising an envelope having an end-wall, a fluorescent screen on said end-wall, a source of electrons positioned remotely from the end wall, a shield electrode in register with said source of electrons, a plurality of similar annular electrodes in register with said source of electrons, a plurality of dissimilar hollow conical electrodes, a hollow shielding electrode intermediate the first and second plurality of electrodes, and deflecting electrodes positioned within the shielding electrode.
